UNITED STATES PATENT OFFICE.

FRANK P. GALLIPOLI, OF NEW YORK, N. Y.

DEVICE FOR PRODUCING AND DISPENSING LATHER.

Application filed December 20, 1922. Serial No. 608,116.

To all whom it may concern:

Be it known that I, FRANK P. GALLIPOLI, a subject of the King of Italy, and a resident of the city of New York, borough of the Bronx, in the county of Bronx and State of New York, have invented a new and Improved Device for Producing and Dispensing Lather, of which the following is a full, clear, and exact description.

10 This invention relates to devices for producing and dispensing a liquid or semi-liquid composition or mixture and refers more particularly to a device for producing and dispensing lather.

15 Heretofore it has been the common practice to employ shaving mugs in which the soap in cake form is arranged and mixed with water by means of the usual shaving brush for producing and applying the lather 20 to the face. In contradistinction to this practice, the present invention contemplates a receptacle or container in which the soap and water are placed, the same being then agitated to produce a lather and means being provided in connection with said receptacle for ejecting the lather thus produced to dispense the same in a proper quantity on the brush.

It is therefore one of the principal objects of the present invention to provide a 30 device for effecting the sanitary production and dispensation of shaving lather in public barber shops whereby the danger of infection to the patrons is reduced to a minimum.

As a further object the invention contemplates a device of the character described which is extremely simple in its construction and mode of operation and which is highly 40 efficient for the purpose for which it is intended.

With the above recited and other objects in view, the invention resides in the novel construction set forth in the following 45 specification, particularly pointed out in the appended claims and illustrated in the accompanying drawing, it being understood that the right is reserved to embodiments other than those actually illustrated herein 50 to the full extent indicated by the general meaning of the terms in which the claims are expressed.

In the drawing—

Figure 1 is a perspective view of a lather 55 producing and dispensing device constructed in accordance with the invention.

Fig. 2 is a vertical sectional view therethrough.

Referring to the drawing by characters of reference, 10 designates a cylindrical container or receptacle body which is provided at its upper end with an annular inwardly projecting flange 11 and which is exteriorly threaded as at 12 at its lower end to receive a removable fixed bottom or base 13. An axially movable disk or plunger 14 snugly fits within the body 10 and is provided with a filling opening 15 having a closure cap 16. The disk or plunger 14 is further provided with a discharge spout 17 the same being preferably detachably associated with the disk by virtue of the frictional telescopic engagement of its enlarged lower end 18 within the boss 19 formed on the disk. The disk is normally maintained at the upper end of the body 10 by means of springs 20 which engage and coact with a crossbar 21 attached to the disk or plunger by vertical connecting rods 22. The crossbar is guided in its movement by the guide rods 23 which extend through the apertured opposite extremities 24 of the crossbar and which rods 23 are rigidly connected at their lower ends to the body 10. The springs 20 encircle 85 the guide rods 23 and exert a tension between the shoulder 25 at the lower end of the guide rods and the apertured extremities 24 of the crossbar 21. At the upper ends the guide rods 23 are provided with 90 heads 26 which limit the expansion of the springs and prevent entire disengagement of the apertured ends 24 from said guide rods. The flange 11 further serves as a 95 stop and abutment for preventing the movement of the disk or plunger 14 entirely from the upper end of the body 10.

In use and operation of the device, the soap in either liquid, cake or powdered form is introduced into the container body 100 either through the filling opening 15 or the bottom end. The water is then introduced through the filling opening 15 by removing the cap 16 and replacing the same. The entire device is then shaken to agitate the 105 contents for the purpose of producing the lather. To dispense the lather, the operator using the crossbar as a manipulating means presses downwardly thereon against the action of the springs 20 to advance the 110 disk or plunger 14 toward the bottom of the container or receptacle 10, thereby forcibly

ejecting the lather through the spout 17 and onto the shaving brush or palm of the hand.

It will thus be seen that a device is provided which affords a highly effective and sanitary method of producing and dispensing lather which is especially designed for use in public barber shops.

I claim:

1. A device of the character described comprising a receptacle body of cylindrical formation, a removable closure cap at the lower end of said body, an axially movable plunger disk within said body, a discharge spout connected to and communicating with said body, said discharge spout projecting upwardly therefrom and provided with an outwardly projecting downturned discharge end disposed laterally from the side of the receptacle body, a cross bar connected with the plunger disk in superposed relation thereto, vertically disposed upstanding

guides extending through the opposite ends of the cross bar, means for normally projecting the plunger disk upward, and means for limiting the upward movement of the plunger disk.

2. A device of the character described comprising a cylindrical receptacle having a closed lower end and an open upper end, an inwardly extending annular flange at the upper end of said container, an axially movable plunger disk fitting within said receptacle, a discharge spout in said plunger disk, said plunger disk having a filling opening and a closure cap therefor, and means for normally advancing and for maintaining the plunger disk at the upper end of the receptacle and in engagement with the flange, said plunger disk adapted upon downward movement toward the closed lower end of the receptacle, to forcibly eject the contents through the spout.

FRANK P. GALLIPOLI.
